COMBINED HORN AND LIGHTS FOR A BICYCLE OR THE LIKE

Homer L. Mueller, Rocky River, Ohio, assignor to Amer-
ican Machine and Foundry Company, a corporation of
New Jersey

Application October 15, 1957, Serial No. 48,104

Term of patent 14 years

(Cl. D48—24)

Fig. 1 is a top plan view of a combined horn and lights for a bicycle or the like, showing my new design;

Fig. 2 is a side elevation thereof, with the brackets omitted for convenience of illustration only.

Fig. 3 is a front end elevation thereof.

Fig. 4 is a rear end elevation thereof, with the brackets omitted for convenience of illustration only.

The dominant features of my design reside in the portions shown in full lines.

I claim:

The ornamental design for a combined horn and lights for a bicycle or the like, as shown and described.
